TABLE LEG

Richard Schwarz, Livingston, N.J., assignor to Bro-Dart
Industries, Inc., Newark, N.J., a corporation of New
York

Filed Oct. 10, 1962, Ser. No. 72,062

Term of patent 14 years

(Cl. D33—14)

FIG. 1

FIGURE 1 is a perspective view of a table leg showing my new design;

FIGURE 2 is a horizontal cross-sectional view taken on line 2—2 of FIGURE 1; and

FIGURE 3 is an enlarged perspective view of the lower end of the leg.

The top surface of the rectangular plate member is plain and unornamented.

I claim:

The ornamental design for table leg substantially as shown and described.
